UNITED STATES PATENT OFFICE

CHARLES H. GURNEY, OF CHICAGO, ILLINOIS, ASSIGNOR TO THE CAPITAL MANUFACTURING COMPANY, OF SAME PLACE.

DESIGN FOR A TACK-PULLER.

SPECIFICATION forming part of Design No. 19,981, dated July 1, 1890.

Application filed May 21, 1890. Serial No. 352,663. Term of patent 14 years.

To all whom it may concern:

Be it known that I, CHARLES H. GURNEY, a citizen of the United States, residing at Chicago, in the county of Cook and State of Illinois, have invented and produced a new and original Design for Tack-Drawers, of which the following is a specification.

The object of this design is to provide a novel and ornamental tack-puller, and the leading features thereof reside in a looped handle-rod which is obovate in outline and has its narrow end extended into a conically-shaped duplex spiral, one of which spirals extends beyond the other as a cylindrical shank, which is curved laterally and terminates in a bifurcated foot-piece.

In the accompanying drawing, illustrating my design, the figure is a perspective view of the tack-puller.

20 In the drawing, the reference-numeral 1 indicates the looped handle-rod, which is obovate

in outline, with its narrow end extending into the conically-shaped duplex spirals 2 and 3, one of which spirals extends beyond the other spiral as the cylindrical shank 4, which is 25 curved laterally, as at 5, and terminates in a bifurcated foot-piece 6, having the thin edge 7.

The conically-shaped duplex spiral, in connection with the obovate looped handle-rod, cylindrical shank, and bifurcated foot-piece, 30 produces a tack-puller of ornamental and distinguishing appearance.

What I claim is—

The design for a tack-puller, substantially as shown and described. 35

In testimony whereof I have affixed my signature in presence of two witnesses.

CHARLES H. GURNEY.
